(57) **CLAIM**

I claim the ornamental design for a steering wheel, as shown and described.

DESCRIPTION

FIG. 1 is a front perspective view of the steering wheel; FIG. 2 is a rear perspective view of the steering wheel; FIG. 3 is a front plan view of the steering wheel; FIG. 4 is a right side view of the steering wheel; FIG. 5 is a rear plan view of the steering wheel; FIG. 6 is a left side view of the steering wheel; FIG. 7 is a top end view of the steering wheel; and, FIG. 8 is a bottom end view of the steering wheel. The broken lines shown in FIGS. 1-8 illustrate openings formed in the steering wheel and form no part of the claimed design.

1 Claim, 6 Drawing Sheets(56)
